Tom Fitzgibbon

UNITED STATES PATENT OFFICE.

TOM FITZGIBBON, OF CHICAGO, ILLINOIS, ASSIGNOR OF ONE-HALF TO
THOMAS COGAN, OF GENESEO, ILLINOIS.

RAIL-JOINT CHAIR.

SPECIFICATION forming part of Letters Patent No. 740,115, dated September 29, 1903.

Application filed April 1, 1903. Serial No. 150,655. (No model.)

To all whom it may concern:

Be it known that I, TOM FITZGIBBON, a citizen of the United States, residing at Chicago, in the county of Cook and State of Illinois, have invented certain new and useful Improvements in Rail-Joint Chairs, of which the following is a specification.

This invention relates to railways, and particularly to rail-joint chairs adapted to connect and hold rail ends firmly together without bolt-holes in the rails or in any part of the chair.

The object of the invention is to provide a boltless hinged or pivoted rail-joint chair controlled by a pawl carried by one of the hinged parts and working against the other hinged part.

A further object of the invention is to provide in lieu of the usual fish-plates a rail-chair comprising a pair of plates hinged or pivoted together and a gravity-pawl carried by one of the plates and engaging the other plate to lock the plates together and to the rails.

A still further object of the invention is to provide a rail-joint chair with a controlling-pawl operated by gravity to close the chair parts on the rails and lock them and to be operated by hand to unlock or loosen the grip of the chair parts on the rails.

With these objects in view the invention consists in the novel construction and arrangement of parts and resides, essentially, in the peculiar hinge or pivot connection and the arrangement of the pawl.

In the accompanying drawings, forming part of this application, Figure 1 is a side elevation showing the application of the chair. Fig. 2 is an inverted plan view of the chair. Fig. 3 is a cross-section on the line $x-x$, Fig.

40 1. Fig. 4 is a cross-section on the line $y-y$, Fig. 1. Fig. 5 is a perspective view of the pawl-plate. Fig. 6 is a similar view of the other plate.

The same numeral-references denote the same parts throughout the several views of the drawings.

The rails are of ordinary shape and construction, having a tread 1, web 2, and base 3, the latter fitting under a shoulder 4 of the

50 chair-plates 5 and 6. The plate 5 has a depending flange 7, provided with a hinge or

pivot member 8 and a cavity having ridges or serrations 10, said member having an opening 11. The plate 6 has a like flange 12 and a lug or projection 13, working in the cavity 9 and provided with hinge or pivot pins 14, working in the pivot member 9.

One of the essential features of the invention is the pawl 15 and its co-operation with the chair-plates in their opening and closing. 60 The pawl is pivoted in a recess 16 of the lug or projection 13, so that it may swing downwardly by its own weight to engage the ridges or serrations in the cavity to hold the plates in engagement with the rails, and thus lock 65 the chair to the rails and the latter together. To loosen the chair-plates, it is only necessary (by means of the opening 11) to push the pawl upwardly on its pivot sufficient for it to disengage the surface of the plate-cavity. The chair-plates may then be opened on their hinge or pivot partially or fully, as occasion may demand.

It is obvious that in applying the chair to laid rails it is placed under and around the 75 rail ends between the railroad-ties, so that the latter will not interfere with its locking and unlocking movements, and that the pawl works within the hinge or pivot parts and is accessible through the opening 11 without 80 separating said parts.

Having thus described my invention, what I claim as new, and desire to secure by Letters Patent, is—

1. A rail-chair comprising a pair of plates 85 hinged or pivoted together so as to be opened and closed against the rails, and a pawl carried by one of the plates and engaging the other plate to lock the plates in closed position.

2. A boltless rail-chair comprising a pair 90 of plates, a hinge or pivot member, on each plate, and a pawl carried by one of said members and working against the other member to lock the plates to the rails.

3. In a rail-chair, the combination with the 95 plates having depending flanges, and connections between the flanges to hinge or pivot the plates together, of a pawl carried by one of the flanges and working against the other flange.

4. In a rail-chair, the combination, with the plates having depending flanges, a lug or pro-

jection on one flange, hinge or pivot pins on the lug, and a bearing on the other flange for said pins, of a gravity-pawl pivoted to said lug and working on said bearing and in a cavity of the bearing-plate.

5. In a rail-chair, the combination, with the plates having depending flanges, of a hinge or pivot connection between the plates comprising a bearing formed on one of the flanges 10 and having an opening therethrough, a recessed lug on the other flange and provided

with hinge or pivot pins working in said bearings, and a gravity-pawl pivoted in the recess over the opening to engage the said bearing-flange.

15

In witness whereof I hereunto set my hand in the presence of two witnesses.

TOM FITZGIBBON.
